Black+Decker Electric Cold Water Pressure Washer, available in Amazon.com, customer review oldest date Apr. 2, 2022 [online], [site visited Jul. 12, 2023], Available from the internet URL: <https://www.amazon.com/BLACK-DECKER-Electric-Pressure-BEPW1600/dp/B09NLCXR5S> (Year: 2022).*

Primary Examiner — Jennifer Rivard*Assistant Examiner* — Jennylo M Binas(74) *Attorney, Agent, or Firm* — John Yun(57) **CLAIM**

The ornamental design for a pressure washer as shown and described.

DESCRIPTION

FIG. 1 shows a front perspective view of a pressure washer showing the new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines shown in the figures are for the purpose of illustrating portions of the pressure washer and form no part of the claimed design.

1 Claim, 8 Drawing Sheets(56)
